UNITED STATES PATENT OFFICE

JEAN DELATTRE-SEGUY, OF CHICAGO, ILLINOIS, ASSIGNOR TO UNIVERSAL OIL PRODUCTS COMPANY, OF CHICAGO, ILLINOIS, A CORPORATION OF SOUTH DAKOTA

PROCESS FOR HYDROCARBON OIL CONVERSION

Continuation of application Serial No. 92,679, filed March 6, 1926. This application filed June 3, 1929.
Serial No. 368,123.

This application is a continuation of my application Serial No. 92,679, filed March 6, 1926.

This invention relates to improvements in process and apparatus for hydrocarbon oil conversion, and refers more particularly to the idea of superheating portions of the volatilized fractions of the oil and subjecting said superheated portions to dephlegmating action.

In systems for the conversion of hydrocarbon oil, there is often a tendency to produce an objectionably high percentage of fixed gases as well as an objectionable quantity of carbon, even in the tube and drum type of apparatus where a large drum is provided for the collection of carbon.

This is particularly true when maximum yields of distillates are desired having anti-knock properties, such as aromatic hydrocarbons.

One of the objects of my invention is to prevent over-cracking of the less refractory constituents of the oil while producing a distillate possessing desirable anti-knock qualities, being of high compression ratio and of desirable volatility. More specifically, my invention contemplates the superheating of portions of the vapors generated in the system and the passage of said superheated vapors into the dephlegmating zone to cause a re-combination of the superheated vaporous fractions with those vapors passed directly from the system into the dephlegmating zone. This materially increases the reaction and the yield of light distillate. The present invention contemplates that all or any portion of the vapors produced in the system may be superheated, if desired.

In the drawings,

Fig. 1 is a side elevational view, partly in vertical section, of an apparatus for carrying out my invention, and

Fig. 2 is an enlarged detail view of a carbon separating device interposed in the superheated vapor line.

Referring more in detail to the drawings, charging stock from any suitable source of supply (not shown) is drawn through the line 1 and forced by the pump 2 through the

line 3 to the heating tube 4, or by proper regulation of the valves 5 and 6 may be diverted and passed through the line 7 communicating with the upper part of the vertical dephlegmator 8. The stream of raw oil may be divided and a portion passed through both of the lines 3 and 7. The heating tube 4 is mounted in the furnace 9 and may be heated by means of the burner 10. The furnace 9 and burner 10 are diagrammatically shown. The oil passing through the heating tube 4 is heated to a conversion temperature and is passed through the transfer line 11, controlled by valve 12, to the enlarged expansion drum 13 which may be provided with upper and lower manholes 14, and liquid residue draw-offs 15, controlled by valves 16, said liquid residue draw-offs being disposed at various heights along the wall of the drum 13. This drum may be unheated and is preferably insulated, although the invention contemplates that it may be heated, if desired. Vapors may be drawn off through the vapor outlet line 17, in which is interposed the valve 18, said line 17 communicating with the lower portion of the vertical dephlegmator 8. After passage through the dephlegmator 8, the vapors which still remain uncondensed may be withdrawn through the line 19, controlled by valve 20, passed through condensing tube 21 mounted in condenser box 22, and the condensed liquid may be collected in the receiver 23. The receiver 23 may be provided with pressure relief pipe 24, controlled by valve 25, and with liquid draw-off pipe 26, controlled by valve 27. The condensed liquid instead of being withdrawn through the line 26 may be returned to the top of the dephlegmator and may be utilized as a cooling medium by being withdrawn and passed through the line 28, in which is interposed a pump 29 and valve 30.

It is to be noted that by proper manipulation of the valves 6 and 30, a desirable amount of charging stock or condensed liquid may be returned to the top of the dephlegmator 8 for cooling purposes. The liquid from the bottom of the dephlegmator 8 may pass down through the reflux leg 31 and returned to the system through the line 3, either under pump

pressure or under its own hydrostatic head pressure. For this purpose, there is provided a by-pass line 32 having a valve 33 interposed therein, or the valves 34 and pump 35.

As one of the features of the present invention, all or a portion of the vapors being released in the expansion drum 13 may be withdrawn through the line 36, controlled by valve 37 and in which is interposed a pump 38, the line 36 communicating with a heating tube 39 located in the upper part of the furnace 9 and heated by means of the burner 40. These vapors passing through the tube 39 may be superheated, the temperature being regulated according to the conditions of the operation and the desired results. The vapors after being superheated in the tube 39 may pass through the transfer line 41 and directed to header A. This header A communicates, through lines B in which are interposed valves B', with carbon separators C, shown more particularly in Fig. 2. By suitable regulation of the various valves B' the superheated vapors can be passed to any one of the carbon separators C interposed in the respective lines B. Provision is made for directing the vapors to these alternate carbon separators so that in the event one of the carbon separators becomes charged with carbon, it can be cut out of operation and another one cut into operation, it being understood that the filled separator can be cleaned while it is out of operation. Each carbon separator C may be provided with a screen C'. The particular construction of these carbon separators is not of any specific importance in the present invention. Hence they have been shown merely diagrammatically. From the carbon separator C through which the vapors are being passed, they are directed to the common line 42 in which are interposed valves 43. Valves D' are interposed in lines D leading from each carbon separator. Discharging into the lower portion of the dephlegmator 8 the outlet may be in the form of a spray, if desired. Intermediate the lines 42 and 17 there may be interposed a connecting line 44 having a valve 45 interposed therein.

It will be readily apparent that the superheated vapors are introduced into the dephlegmator substantially free of carbon. The particular temperature and pressure conditions which will be maintained in the various parts of the apparatus, for instance, the heating tube 4, drum 13, dephlegmator 8, condenser 22, heating tube 39, and also the proportion of the vapors superheated, will vary depending on the character and nature of the oil being treated and the results desired, as well as the characteristics and composition of the pressure distillate desired, it being understood that as a general result of the operation, the higher the temperatures in the vapor superheating tube 39, or the larger

the proportion of vapors passed through said tube, the larger will be the proportion of aromatic and naphthene hydrocarbons in the final distillate.

The nature and character of my invention can perhaps be best understood by comparing it with a process in which no portion of the vapors is superheated prior to being passed to the dephlegmating zone. The following may be cited as an illustrative example of a run carried out in the present apparatus without superheating the vapors. A Mid-Continent fuel oil having a Baumé gravity of 25.1° was subjected in the heating tube 4 to a temperature of substantially 880° F., while the temperature in the reaction drum 13 averaged substantially 860° F. The vapors passing through the line 17 to enter the dephlegmator were at a temperature of substantially 850° F. This run was carried out under a superatmospheric pressure of substantially 150 pounds. This resulted in 40% of the charge being converted into motor fuel having an end point of 437° F., and a compression ratio of about 5.

For the purposes of comparison, the following illustrative run may be given, in which a portion of the vapors was withdrawn from reaction drum 13, superheated in the tube 39 and passed to the dephlegmator. In this run the same character of oil was treated. The temperature to which the oil was subjected in the heating tube 4 was substantially 730° F. The vapors which were superheated prior to being passed to the dephlegmator were raised to a temperature of substantially 1100° F. These vapors were in the proportion of about 30% of the amount of the oil passed through the heating tube 4, on the basis of weight. The average temperature maintained in the reaction drum was substantially 650° F., while the vapors leaving the drum 13, to be directed either to the dephlegmator or into the vapor heating tube 39, were at a temperature of substantially 640° F. In carrying out this last mentioned run, substantially 50% of the oil charge was converted into motor fuel, having substantially the same distillate range as that in the preceding run but in addition the compression ratio was increased to 6.5, probably due to an increase in the percentage of aromatic and naphthene hydrocarbons. The volatility of the resulting motor fuel was also improved.

The superheating of vapors in the tube 39 produces an increased amount of aromatic and naphthene compounds. The quantity thereof can be controlled by the amount of vapors passed through the heating tube 39, or by the conditions of temperature and pressure maintained therein. It will be instantly apparent that by controlling the numerous valves and pumps located in the system, a uniform pressure may be maintained, or if

desired, differential pressures may be maintained.

The anti-knock property of motor fuel depends on several factors, the most important 5 of which is the chemical composition. The higher the proportion of aromatic and napthene compounds in a motor fuel, the greater are its qualities as an anti-knock fuel. For instance, an increase of 6% in aromatics gives 10 an increase of 0.3 in the highest compression ratio. It is believed that the present invention materially improves the volatility of the motor fuel produced by passing portions of the vapors produced in the system through 15 a superheating zone, and combining this portion in the dephlegmator with the vapors from the system which have not been superheated.

I claim as my invention:

20 1. A method of hydrocarbon oil conversion comprising passing a stream of oil through an elongated passageway located in a furnace wherein the oil is heated to a cracking temperature, in then transferring the heated oil 25 into an enlarged reaction drum where substantial separation of vapors takes place, in withdrawing a portion only of said vapors and subjecting them to a superheating temperature while removing the remaining vapors for dephlegmation, in passing said superheated vapors to a dephlegmating zone, in subjecting all the vapors separated from the oil in the process to dephlegmation in said dephlegmating zone, in removing and condensing the vapors which are still uncondensed after passage through the dephlegmating zone.

20 2. A method of hydrocarbon oil conversion comprising heating a stream of oil in an elongated passageway to a cracking temperature, passing said heated oil to an enlarged expansion drum where substantial separation of vapors takes place, in withdrawing portions of said vapors and passing 45 the same directly to a dephlegmator, in withdrawing other portions of said vapors and superheating same, in then mixing in the dephlegmator the superheated vapors with the vapors which have been passed directly 50 to said dephlegmator, and in withdrawing and condensing the dephlegmated vapors.

3. A method of hydrocarbon oil conversion comprising passing a stream of oil through an elongated passageway located in a furnace 55 wherein the oil is heated to a cracking temperature, in then transferring the heated oil into an enlarged reaction drum where substantial separation of vapors takes place, in withdrawing a portion of said vapors and 60 subjecting them to a superheating temperature, in passing said superheated vapors to a dephlegmating zone to which additional vapors are continuously introduced from said enlarged reaction zone, in subjecting the vapors 65 to dephlegmation, in removing and condens-

ing the vapors which are still uncondensed after passage through the dephlegmating zone, and in maintaining a superatmospheric pressure on the oil and vapors under treatment.

4. A method of hydrocarbon oil conversion comprising heating a stream of oil in an elongated passageway to a cracking temperature, in passing said heated oil to an enlarged expansion drum where substantial separation of 70 vapors takes place, in withdrawing portions of said vapors and passing same directly to a dephlegmator, in withdrawing other portions of said vapors and superheating same, in mixing in the dephlegmator the superheated vapors with the vapors which have been passed directly to the dephlegmator, in withdrawing and condensing the dephlegmated vapors, and in maintaining superatmospheric pressure on the oil and vapors 75 under treatment.

In testimony whereof I affix my signature.
